INVENTOR
Paul C. Smalley,
BY
Frank C. Fischer.
ATTORNEY

UNITED STATES PATENT OFFICE.

PAUL C. SMALLEY, OF NEWARK, NEW JERSEY.

FLASH-LIGHT DEVICE.

Application filed March 29, 1919. Serial No. 286,185.

To all whom it may concern:

Be it known that I, PAUL C. SMALLEY, a citizen of the United States, residing in the city of Newark, in the county of Essex and 5 State of New Jersey, have invented certain new and useful Improvements in Flash-Light Devices, of which the following is a full, clear, and exact description, such as will enable others skilled in the art to which 10 it pertains to make, construct, and use the same, reference being had to the accompanying drawings, and to numerals of reference thereon, forming a part of this specification.

The present invention has particular relation 15 to the arrangement or construction whereby the circuit of a portable electric lamp is closed or opened at will in order that the light may be used as an intermittent flash, or a continuous light.

20 The principal object of the invention is the provision of means of an inexpensive, simple and reliable character and capable of convenient application to any form of portable electric lamp whereby the lamp may be 25 lighted or extinguished.

These objects I perform in the preferred embodiment of my invention, which I have illustrated in the accompanying drawings, to which reference is had, and in which 30 similar reference characters indicate corresponding parts in the several views.

In the drawings,

Fig. 1 represents a side elevation of a portable lamp showing the circuit closer in 35 plan.

Fig. 2 represents a longitudinal section of a portable lamp taken on line $x-x$ in Fig. 1 showing the circuit closer in section.

Figures 3 and 4 represent respectively a 40 plan view and a side elevation of a modified form of spring.

The casing of the lamp is shown at 1, the same being made of insulating material and provided with a threaded metal end 2 which 45 is applied to the exterior of the casing 1 at the front end, and a similar threaded metal end 3 which is applied to the exterior of the casing at the rear end thereof. The batteries are shown at 4 and are held in place 50 by the cap 5 which screws onto the threaded end 3, and, preferably, by the spring 6. The lamp 7 screws into the reflector 8 behind the lens 9 in a well known manner; the whole being secured by a threaded thimble 10 55 which screws onto the threaded metal end 2 at the upper end of the lamp casing 1.

As usual in these devices one terminal of the lamp 7 makes contact at 11 with one terminal of the battery while the other terminal of the lamp is electrically connected 60 to the metal reflector 8. The circuit closing means comprises two portions, one of which is composed of a fixed metal stud 12 riveted to the exterior of the casing 1 and kept in permanent electric connection with one terminal of the lamp by means of the conductor 13 and the reflector 8. The conductor 13 as illustrated in the drawings is secured to the interior of the lamp casing 1 by means of said stud and a similar stud 14. The 65 usual insulating material 15 surrounds the battery cells and prevents their making contact with the conductor 13 or other metal parts projecting into the casing 1.

The other portion of the circuit closer 75 comprises a spring 16 located within a suitable metal box or casing 17. The box or casing 17 together with the spring 16 is fastened to the exterior of the casing 1 preferably by a stud 18, said stud 18 also 80 serving to secure the conductor 19 within the interior of the casing 1. Said box 17 together with the spring 16 is maintained in permanent electric connection by means of the said conductor 19 with the threaded end 85 3 and therefore through the cap 5 and spring 6, with the zinc terminal of the battery. Interposed between the top side of the spring 16 and the inner under side of the box or casing 17 and frictionally and slidably arranged within said casing is a 90 spring 20 provided with upturned ends, and secured to the box or casing 17 by means of a button 21 the shank of which projects through a slot 22 in one end of the casing. 95 To the end of said shank the spring is secured in any desired or convenient manner.

The spring 16 as clearly indicated in the drawings, approximately midway of its length, is provided with an offset portion 100 25 so that the front end of the spring in its normal position is located above the stud 12. The front end of the box or casing 17 is provided with an aperture 23, the metal surrounding the aperture being 105 forced downwardly into the box or casing, and loosely located in said aperture is a button 24 which normally rests upon the top of the forward end of the spring 16 and the shank of which projects through the 110 aperture 23 in the said casing; the end of the shank preferably lying below or in close

proximity to the top of the casing, so as to obviate the liability of accidental closing of the circuit when the device is carried in the pocket of the user. The spring 20 is also provided with two upturned ends in order that when it is secured in the box or casing 17, as previously described, the ends cause an upward pressure against the inner under side of the box or casing 17 which develops sufficient friction to hold the spring in open-circuit condition.

The spring shown in Figures 3 and 4 of the drawings differs slightly from the spring 16 shown in Fig. 2, by being provided with a pressed out portion 26, said pressed out portion 26 being integral with the spring and which is intended to project through the aperture 23 in the box or casing 17, the said construction thereby dispensing with the button 24 which as illustrated in Fig. 2 of the drawings normally rests upon the top of the forward end of the spring 16, and the back of which projects through the aperture 23 in said casing.

When it is desired to operate the lamp and light is desired for long periods, the circuit is closed, and may be kept closed without effort on the part of the user, by moving the button 21 with the attached spring 20 forward in the direction indicated by the arrow, until the upturned end of the spring 20 engages with the offset portion 25 of the spring 16 thereby causing the free end of the spring 16 to contact with the stud 12 and in that manner closing the lamp circuit.

When it is desired to operate the lamp and light is desired for momentary or short periods as for ordinary push-button use it is only necessary to press the push-button 24 in and hold it in so long as the light is required.

It will thus be seen that I have provided a circuit closing means, in which I have reduced the actual number of parts to a minimum; that when assembled, the possi-

bility of the parts becoming separated by careless manipulation has also been reduced to a minimum. The parts are of such shape as to lend themselves readily to manufacture by the use of suitable punches and dies from ordinary sheet metal.

Experience has demonstrated that the organization above described is a practical and efficient one for accomplishing the ends sought by this invention. The construction may, however, be varied in detail by those skilled in such matters, without departing from the invention. I desire to claim the device as broadly as the state of the art will permit, and with no limitations other than such as may be expressed in the claim as that may be allowed.

I claim:

A switch for portable electric lights comprising in combination with the light casing, of a plate fixed on said casing, said plate being raised to produce a chamber having its outer wall parallel with said case, a flat spring having out-turned ends 70 slidably presented to the wall, a button fixed on said spring to project through a slot in the wall and by which said spring may be actuated, a spring contact spaced from said spring, said contact being bent 75 to present its main elements in two different planes, one of the elements being fixed to said casing and the other reaching to the front end of the chamber to be engaged by one of the out-turned ends of said spring 80 whereby it may be flexed to circuit closing position, and a button projecting through an opening in the chamber wall, said button being integral with the adjacent end of said spring.

This specification signed and witnessed 85 this 25th day of March, 1919.

PAUL C. SMALLEY.
